United States Patent

Des. 238,755

Patented Feb. 10, 1976

238,755

PACKAGING CONTAINER

Charles K. Huff, Omaha, Nebr., assignor to Harold Mangelsen & Sons, Inc., Omaha, Nebr.

Filed Aug. 13, 1973, Ser. No. 387,683

Term of patent 14 years

Int. Cl. D9—03

U.S. Cl. D9—171

FIG. 1

FIG. 2

FIG. 3

FIG. 4

FIG. 5

FIG. 1 is a rear perspective view of a packaging container showing my new design;

FIG. 2 is a front elevational view;

FIG. 3 is a side elevational view;

FIG. 4 is a side elevational view showing the side opposite that seen in FIG. 3; and

FIG. 5 is a bottom plan view thereof.

I claim:

The ornamental design for a packaging container, substantially as shown and described.
